SASH LOCK

Melvern L. Dilks, Llanerch, Pa.

Application February 11, 1943, Serial No. 475,487

2 Claims. (Cl. 292—342)

The invention relates to improvements in sash locks for windows. The object is to provide improved means for preventing a rattling or a movement of the sash within the frame after the desired adjustment of the same.

The invention comprises simple and efficient method and means for assembling the device and simple and efficient method and means for mounting the same upon the sash.

The device is adapted for association with almost any form of sash and frame.

Referring to the drawing, which illustrates by way of example suitable means for the embodiment of my invention:

Fig. 1 is a front elevation showing the device in locking position upon the sash.

Fig. 2 is a horizontal section on line 2—2 of Fig. 1.

Fig. 3 is a perspective view of the wedging element.

Fig. 4 is a perspective view showing the method of assembling.

Fig. 5 is a view similar to Fig. 2, but showing a part of formation 7 countersunk in said sash.

Similar numerals refer to similar parts throughout the several views.

Formation 7, of a strip of resilient metal is so bent as to provide the two leaves 10 and 11, normally in slightly convergent planes, but adapted to be wedged or spread apart, by the operation of the sliding wedge element 9.

The inner leaf 10 of formation 7 is adapted to be secured upon the face of the sash 12, adjacent the frame 13. This leaf 10 is provided with suitable holes for receiving the wood screws 15 and 16, which secure the leaf 10 to the sash 12.

It will be noted, that Fig. 2 shows the outer end 17 of leaf 11 extending beyond the outer end 19 of leaf 10, and while the major extension of leaf 11 is inclined to the plane of leaf 10, its outer end 17 is formed so that the said end portion 17 will coincide with the plane of the underside of leaf 10.

This formation makes it possible to utilize the device with a frame and sash presenting a minimum of space between their adjacent surfaces.

As a further improvement in said device the said end or extension 17 may be slightly countersunk in the surface of the sash. This permits of a closer fit between sash and frame for receiving the end 17 of the leaf 11.

A wedge element 9 is slidably mounted between the two leaves 10 and 11 of element 7. This wedge is provided with a thumb-piece 21 for manipulating the same. Said wedge is also pro-

vided with a slot 22 which cooperates with the screw pin 16 for guiding the forward and backward movement of the wedge 9, to cause the separation of the free ends of leaves 10 and 11 and vice versa, for locking and unlocking of the sash and frame.

This screw pin 16 also cooperates with screw 15 in securing the formation 7 to the sash 12.

An important advantage of the arrangement herein described, in addition to the simplicity and efficiency of the device, is that in the locking operation of the extension 17 upon the co-acting surface of the frame 13 the pressure is a simultaneous even right angular pressure, and not a sliding pressure, which would tend to cause abrasion or distortion.

In assembling and positioning the device, it will be noted that the formation 7 is properly positioned upon the sash and secured thereto by means of the screw 15. The thumb-piece 21 of wedge element 9 is introduced between the leaves 10 and 11 and also through the longitudinal slot 14 provided in the leaf 10 (see Fig. 4). The thumb-piece 21 is then twisted to carry the wedge part 9 entirely between the two leaves 10 and 11. A longitudinal slot 14 is also provided in the formation 7 for receiving the neck which joins the thumb-part. This slot serves to guide the movement of the wedge, and also cooperates with screw 16 in maintaining the position of the formation 7.

What I claim is:

1. A sash lock for windows, comprising a resilient body bent to form two leaves, one overlying the other, and in slightly convergent planes, one leaf having an end extending beyond the other leaf-end and wedging means slidably longitudinally between said leaves for separating the same, the said leaf-end that extends beyond the other leaf-end being so shaped as to secure normally an extension in a plane co-existent with the plane of the other leaf-end.

2. A sash lock for windows, comprising a resilient body bent to form two leaves, one overlying the other, said leaves extending in slightly convergent planes, one leaf having an end extending beyond the other leaf-end, said extending end being the only part inserted between the sash and frame, and wedging means slidably longitudinally between said leaves for separating the same, the parts being so arranged and operated as to secure even and simultaneous pressure engagement throughout the respective co-acting areas of the leaf-end and frame.
